UNITED STATES PATENT OFFICE.

HENRY EGGERS, OF DENVER, COLORADO.

AUTOMATIC VARIABLE-RIFFLE BELT CONCENTRATOR.

1,150,257.

Specification of Letters Patent. Patented Aug. 17, 1915.

Application filed January 18, 1913. Serial No. 742,917.

To all whom it may concern:

Be it known that I, HENRY EGGERS, a citizen of the United States of America, residing in the city and county of Denver and

5 State of Colorado, have invented a new and useful Automatic Variable-Riffle Belt Concentrator, of which the following is a specification.

10 My invention relates to a new automatic variable-riffle belt concentrator, and the objects of my invention are: First, to provide an endless belt concentrator, that is provided with a variable riffled concentrating surface, that acts to automatically separate 15 the gangue matter from the mineral particles of ore pulp and concentrates, and saves a very high percentage of the mineral particles of ore pulp. Second, to provide an endless belt concentrator that is provided with sunken or recessed riffles, which are arranged and adapted to automatically, 20 successively, and gradually decrease in their cross sectional area as the belt travels from its ore pulp receiving end to its mineral 25 discharging end. And third, to provide an ore pulp endless belt concentrator that is provided with a flexible belt that can be folded into sunken riffled traveling concentrating surfaces, the riffles of which are arranged to decrease in cross sectional area 30 from its ore pulp receiving end to its mineral discharging end. I attain these objects by the mechanism illustrated in the 35 accompanying drawings, in which:

Figure 1, is a plan view of the improved belt concentrator. Fig. 2, is a side view of the same, looking from the discharge side of the machine. Fig. 3, is an end view of the discharge end of the machine. Fig. 4,

40 is a plan view on an enlarged scale of the rollers which support the belt and form the riffles therein, the belt and strips attached thereto being shown in section. Fig. 5, is a sectional view on an enlarged scale of a portion of the belt, showing the rubber strips attached thereto. Fig. 6, is a similar view showing the strips turned at right angles, and the belt folded into riffles between the 45 strips. Fig. 7, is a plan view of a modification in the means for forming the riffles in the belt. Fig. 8, is an end view looking from the feed end of the device shown in Fig. 7. Fig. 9, is a view of the opposite end to that shown in Fig. 8. Fig. 10, is a perspective view of one of the knife edge bear-

ing plates. And Fig. 11, is a detailed perspective view illustrating a portion of the belt frame, showing one of the suspension rods in engagement therewith.

Similar letters of reference refer to similar parts throughout the several views.

Referring to the drawings,—the numeral 1 designates the supporting structure of my improved concentrator, which is constructed of structural iron, and comprises a rectangular frame 2, parallel U-shaped portions 3 and 4, at opposite ends thereof, which are spaced from the under side of the frame 2, and form therewith supports for the journal boxes 5 and 6, the boxes 5 being adjustable, 65 while the boxes 6 are stationary, and side bars 7 below and parallel with the side bars of the frame 2, the former bars having upturned ends which are secured to the U-shaped members 3 and 4. The U-shaped 70 members are secured to the frame 2, in any suitable manner, such as by plates 8, and the frame 2, and bars 7, are connected by opposite pairs of vertical angle bars 9. The bars 7 are further connected to the side bars 75 of the frame 2, by brace bars 10. At the opposite end portions of this frame, I mount in the journal boxes 5 and 6, shafts 11 and 12, upon which I mount rollers 13 and 14. The roller 14, which is at the feed end of 80 the machine, is provided with a plurality of projecting collar portions 15, and a plurality of alternate grooves 16. The grooves are of even width throughout the length of the drum and are preferably about seven- 85 sixteenths of an inch in width. Both the collar portions and the grooves may be made wider or smaller, as desired. 90

The roller 13, which is positioned at the concentrates discharge end of the concentrator, is provided with alternating collars and grooves 17 and 18 respectively. The collars, however, of the roller 13, are each provided with a hub portion or step 19, which portions constitute the bottom bearing 95 seats for the automatically progressively 100 closing riffles, which will be described more fully hereinafter.

Beneath the roller 13 is mounted a roller 20, of the same diameter as the rollers 13 and 14, but grooved to correspond to the roller 14. The shaft of this roller is journaled in bearings 21, on the adjacent upturned ends of the bars 7. 105

On the bars 7 adjacent to the rollers 20 110

and 14, are mounted rollers 22 and 25 respectively, and on the brace bars 10 are mounted rollers 23 and 24.

Around the rollers 13, 14 and 20, and over 5 the rollers 22, 23, 24 and 25, is placed a flexible endless belt 26, which is composed of any suitable material, such as special kinds of cloth fabrics or pliable rubber. This belt is considerably wider than the length of the 10 rollers, and is folded into a number of successive small folds to form a series of riffles that automatically decrease in width from the ore pulp feeding end of the belt to its concentrates discharging end, as will be 15 fully described hereinafter. This flexible belt is provided on its inner face with a plurality of strips 27 of rubber or other suitable material, which fit into the grooves of the rollers 13 and 14. These strips are secured 20 to the belt at exactly the center of their widths, and only at their centers, by being sewed thereto by threads or by wire, or by being tacked thereto or by any other suitable means. Consequently each of these 25 strips extends throughout the entire circumference of the belt. These rubber strips are thus free to be turned up edgewise to fit into the grooves of the rollers 13 and 14, and when they are so turned they fold a portion 30 of the width of the belt between them, which folded portions rest upon the peripheries of the collar portions of the said rollers, and as these strips are secured along their centers to the belt, the belt is carried down the side 35 of one strip to the adjacent collar of the roller, then across the top of the collar and up the opposite side of the adjacent strip, and over its top edge, and down its side and across the next collar and again up the side 40 of the next strip, and so on across the rollers, the folded portion between the strips forming riffles 28, that receive and hold the ore pulp, which is fed onto it from the feed hopper 29 through suitable discharging 45 apertures 30 formed along its lower edge. These riffles fill up with ore pulp, which is finely crushed ore mixed with sufficient water to make a flowing stream, the ore flowing onto the flat top portions of the belt that 50 rest on top of the edges of the strips, and flowing into the riffles adjacent to the feed hopper, and then overflowing from them across the surface of the belt. The belt is 55 given a variable speed traveling movement, as well as a variable stroke reciprocal movement, which moves the ore along in the riffles and across the table, as will be fully described hereinafter.

As the belt travels with a reciprocal traveling movement from its feed end to its discharge end, the riffles formed between the strips of the belt at the feed end and the strips and collars of the roller at the discharge end gradually and automatically 60 grow narrower in width, which causes the

ore pulp in them to be moved and its lighter gangue and mineral particles to be forced up from among the heavier particles of ore pulp within them, and discharged from them under the natural force of gravitation, 70 and the reciprocal and traveling movement of the belt, which tends to cause the heavier particles of the mineral to settle in the bottom of these riffles, and they naturally force the light gangue matter and the lighter mineral particles up out of the said riffles, and these are washed across the belt by wash water, which is distributed onto the belt along its ore-pulp feeding side from a water distributing box 31, which is provided with 80 water distributing apertures 32. The water distributing box is supported independently of the belt by suitable brackets 33, which form parts of standards 34, which support the belt frame, as will be hereinafter set 85 forth. The ore pulp feed hopper is suitably secured to the adjacent side of the belt frame. The grooves 18 of the roller 13 are twice the depth of those in the roller 14, or the same depth as the thickness of the strips 90 27 on the belt, and the annular hubs or shoulders 19, on this roller, upon which rest the portions of the belt forming the bottoms of the riffles, are of such diameter as will 95 give the same depth to the riffle at this end of the machine as at the feed end thereof, as will be understood by reference to Fig. 4.

The riffle forming portions of the belt that lie between the strips 27 and the collars of the roller 13, and on the tops 100 of the hubs 19 of said roller, are of much less width at the mineral discharging end of the belt than at its feed end. This reduction in the width of the riffle is caused by a series or plurality of rollers 34^A, positioned intermediate of the rollers 13 and 14, and spaced at a short distance apart along the length of the belt. These rollers 34^A are provided with shafts and are journaled 105 in suitable boxes 35, that are secured to the sides of the belt supporting frame 2 of the concentrator. These rollers 34^A are each provided with annular shoulders or hubs 36, which are arranged in alinement with the hubs and collars respectively of the rollers 13 and 14, and they are also each provided with grooves 37, in line with the grooves in the rollers 13 and 14. All of these rollers 110 with the exception of the first two rollers 38 from the roller 14, are provided with flanges 39, which increase progressively in thickness from the feed end of the machine to its discharge end, which are in line with the collars or flanges 17 of the roller 13, and they make a continuous straight line or 115 row of grooves and collar flange portions from the roller 13 to the roller 14, and the riffle making strips of the belt travel in the grooves of all of these rollers, and the belt 120 travels on top of the collar portions.

The sides of the riffles, as the belt travels along from the rollers 14, engage the sides of these flanges of the first flanged roller, and are pushed in, and the said riffles are narrowed in cross section. The loose portion of the belt that folds down and forms one side of a riffle, is crowded over toward its opposite side, which is sewed or otherwise secured to one of the rubber strips, and the flange on the next roller is a little thicker and crowds the loose fold of the belt a little farther over toward the secured side of the riffle, and the flanges of the next roller are a little thicker than those of the second flanged roller and consequently move the loose sides of the riffles of the belt a little closer to their opposite sides that are secured to the rubber strips of the belt, and consequently decrease the cross sectional areas of the riffles. Thus the flanges of each succeeding roller toward the roller 13, are a trifle thicker and reduce or decrease the cross section areas of the riffles, as the belt travels from the roller 14 to the roller 13, which is the mineral discharge end of the belt, where each riffle is reduced to about one-fourth of the cross sectional area of the riffle at its feed end, which is preferably about one-half of an inch wide and about a quarter of an inch deep. At the mineral discharge end, the riffles are of the same depth, but are narrowed by the flanges to a width of about one-eighth of an inch. It will thus be seen that the belt riffles are of the same depth through the length of the belt, but are decreased in width automatically by the successively and progressively increasing thickness of the flanges of the rollers between the rollers 13 and 14. After the belt leaves the mineral discharging roller 13, it passes down and around the roller 20, which is provided with collars and grooves of the same size and arrangement as those on the roller 14, and the belt riffles open out to the same width they have on the roller 14, and the belt in passing around the roller 20 dips into a tank 40, containing water, and the mineral concentrates are washed from it and from its riffles. Or if desired a spray of water may be used to wash these concentrates from the belt into the tank. I do not illustrate this spray, as it does not form any part of my present invention. From the roller 20, the belt travels over the supporting rollers 22, 23, 24, and 25, which are supported in the manner above described, upon the frame of the concentrator. At the feed side of the belt, the ends of the rollers 13 and 14 are provided with enlarged outwardly extending flanges 41, which are adapted to turn the feed side edge of the belt slightly upward to prevent ore pulp or mineral from working over that side edge of the belt. The belt frame is provided with a supporting and tilting mechanism which comprises

standards 34, having right angled upper ends, provided with holes 42, through which rods 43 extend loosely. Nuts 44 are threaded to the upper ends of the rods, and knife edge washers 45 are placed on the bolts between the nuts and the top of the standard, upon which they rest.

The lower ends of the rods 43, are bifurcated, and the bifurcated portions are upwardly bent to form hooks 46, which engage the heads 47 of T-shaped arms or projections 48, which extend from plates 49, which are bolted or otherwise secured to the pairs of vertical angle bars 9, adjoining the side bars 7, as fully shown by Fig. 11. The belt frame is thus suspended from the upper ends of the standards 34, by the said rods 43, carrying the knife edge plates or washers, shown in Fig. 10, and which bear upon the said upper ends of the standards, whereby a reciprocating movement may be imparted to the table, in a manner to be presently set forth. The belt frame may also be tilted to slant downward from its feed side, by screwing down the nuts upon the end of the rods 43, on the said feed side of the frame, by which the frame is lifted on that side, as will be understood.

As previously stated, the bearing boxes 5 for the shaft of the roller 13, are adjustable, and to these boxes are connected the inner ends of threaded rods 50, in such manner that the rods may be turned. The outer portions of these rods extend through threaded blocks 51, which are secured between the U-shaped frame member 3, and the rectangular frame 2, and their outer ends are provided with hand wheels 52. By turning the hand wheels 52, the boxes 5 are moved in or out, as the case may be, carrying with them the roller 13. In this manner, the tension on the belt may be regulated, as will be fully understood by reference to Figs. 1 and 2. The belt frame may be reciprocated in any suitable way. I have, however, illustrated a driving mechanism, which consists of a driven shaft 53, mounted in suitable bearings 54, which are bolted to a frame 55, adjacent the feed end of the belt frame. This frame 55 is preferably supported upon foundation beams 56, which also support the standards 34, from which the belt frame is suspended. The shaft 53 carries tight and loose pulleys 57 and 58, respectively, which are adapted to be connected by a belt—not shown—with the pulley of a drive shaft.

A common form of eccentric 59 is also mounted on this shaft, having a rod 60, which is pivotally connected at its opposite end to a bracket arm 61, secured to the adjacent end of the belt frame. The eccentric is designed to impart short, quick reciprocations to the belt frame, as will be understood.

A friction pinion or disk 62, is slidably

mounted on the shaft 53, near the end thereof, which projects beyond the discharge side of the table, the shaft being provided with a feather key 63, which passes through the disk 62, and locks the same to the shaft so as to rotate therewith, but which permits a sliding movement of the disk, as will be understood. This disk is formed with a hub 64, having an annular groove, into which extends one end of a follower 65, which is mounted on a threaded rod 66, which is rotatably mounted in bearings 67, to lie parallel with the shaft 53. The outer end of the rod 66, is provided with an operating hand wheel 68, and when the rod is turned, the follower 65 is moved backward or forward, as the case may be, carrying with it the friction disk 62.

The periphery of the disk 62, is in frictional contact with the face of a friction wheel 69, which is rigidly mounted on one end of a shaft 70, which is supported in bearings 71 and 72, on the frame 55, and adjacent standard 84, respectively. The opposite end of the shaft 70 is connected by a universal joint 73, with one end of one section 73^A, of a divided shaft. Upon the opposite end of this section is rigidly secured a sleeve 74, which projects a considerable distance beyond the said end. One end of the other section 75, of this divided shaft, fits slidably in the said sleeve, but so as to be turned by the sleeve, any suitable means for effecting this operation being employed, such as a feather key 76, as shown in Figs. 1 and 2.

The opposite end of the shaft section 75, is connected by a universal joint 77, with a short shaft 78, which is mounted in bearings 79, secured to the U-shaped frame member 3. The opposite end of the shaft 78, is provided with a worm pinion 80, which meshes with a worm wheel 81, on the adjacent end of the shaft carrying the roller 13. Rotary motion is thus transmitted from the shaft 53 to the roller 13, by engagement of the friction pinion 62, with the friction wheel 69, by which the shaft sections 70, 73^A, 75, and 78 are rotated, the latter shaft carrying the worm pinion 80, which turns the worm wheel 81, on the shaft of the roller 13. Thus the belt 26 is moved in the direction of the arrow, and the speed at which it travels is determined by the position of the friction pinion 62, relatively to the axis of the friction wheel 69, as will be understood.

In Figs. 7, 8 and 9, I have shown a modification in the means for forming the riffles in the belt. In this modification, I employ a platform 82, which is rigidly secured to the rectangular frame 2, immediately beneath the belt 26. This platform is adapted to take the place of the rollers 34^A, and to this end is provided with a plurality of parallel grooves 83, which receive the rubber strips

27, on the belt 26. These grooves are formed by spaced strips 84 of wood, which are secured to the platform.

Upon the strips 84, are secured other strips 85, having front edges parallel with 76 and flush with the sides of the grooves 83, next the feed side of the belt, while their opposite edges are divergent from their front edges, the said strips being narrowest at the feed end of the belt, and widest at the 75 discharge end thereof, the walls formed by these divergent or slanting edges and the sides of the strips 27 in the adjacent grooves 83, constituting riffle-forming guides, by which the portions of the belt between the 80 strips 27 are automatically folded into riffles, which decrease in width from the feed end of the belt, to the discharge end thereof.

The operation of my improved variable riffle belt concentrator, is as follows: The 85 ore pulp flows into the feed hopper through a launder—not shown—from a source of supply, and distributes itself upon the belt through the apertures along the lower side of the feed hopper. This ore pulp flows 90 naturally across the belt, which is adjusted to an inclination to suit the character of the ore being treated, and this ore pulp as it flows across the belt, enters and fills the variable riffles that are formed in the belt by the 95 automatic folding action of the rollers, as the belt passes over them from the feed-end roller 14 to the mineral discharge roller 13, and the belt is also given through its driving mechanism a reciprocating movement, 100 which can be regulated for more or less throw as desired. Consequently the combination of the transverse flowing movement of the ore pulp down the inclined belt, and the reciprocal movement of the belt, causes the 105 ore pulp to feed along the belt in the riffles, at the same time that a portion of it is feeding across the belt, and as the result of these two movements of the ore pulp, it flows in a diagonal line from the feed hopper of the 110 machine to the diagonally opposite lower corner of the belt, while the mineral particles settle in the riffles and are caught by them, and under the reciprocating action of the belt the heavier particles sift down to 115 the bottom of the riffles, and the lighter gangue matter and the lighter particles of mineral work up in these riffles to the top, and are carried across the belt and continuously work into and are ejected from the 120 upper rows of riffles, until they find a lodgment in the riffles below the upper rows of riffles, which naturally catch the heavier mineral particles. The riffles themselves decrease continuously and gradually, from the 125 feed end of the table to the concentrated mineral discharging end of the belt, and this gradual and continuous narrowing and decrease in the cross section area of these riffles, also tends to cause the mineral par- 130

ties that would naturally find lodgment in the bottom of the riffles, to force out and up with a sort of a buoyant action under the reciprocal movement of the belt, and the 5 added influence of a body of wash water, the lighter particles. This wash water is clear water and flows constantly on the table from a water box 31, which is arranged along the upper edge of the belt adjacent to the feed hopper, and the quantity of 10 water admitted to the table can be regulated by any suitable means. As the mineral particles work along toward and to the discharge end of the belt, the heavier particles 15 at all times work, under the action of the belt and the wash water, to eject from among them and from these riffles, the gangue matter and the lighter mineral particles, which become middlings and are known as 20 the middlings product. This product passes off the lower side of the table, near or adjacent to its lower corner 86, the table being tilted to any desired angle to discharge this middling products off at or adjacent to this 25 corner. The mineral in the riffles after it passes over the discharge roller 13, passes down and over the roller 20, and as this roller is arranged to spread and open out these automatically folding and variable size 30 riffles, when they reach the lower roller 20, they are open to their full width, and the mineral falls by gravity into the tank or is washed off by a spray of water or can be naturally washed off by filling this tank with 35 enough water to submerge the belt as it passes around the lower edge of the roller 20. The belt then travels under the machine over the idler rollers, to the end roller 14, the riffles all the time remaining to their full 40 size, and remain this way after they pass over the roller 14 until they strike the flanged rollers that lie along the whole length of the frame of the machine underneath the belt, and these flanges successively 45 and continuously and gradually close and narrow and decrease the width of these riffles automatically, as the belt moves to and passes over the end roller 13.

My invention provides a concentrator that 50 contains within itself the means of providing automatically a variable sized sunken or recessed riffles; that are capable of acting upon the mineral particles that flow into them to aid and assist to separate the gangue 55 matter and lighter mineral particles of an ore pulp from its heavier particles, and thus enable my concentrator to effect a much larger percentage of saving in concentrating ores than has hitherto been attained; and 60 while I have illustrated and described the preferred arrangement and construction of my improved automatic variable riffled belt concentrator, I do not wish to be limited to the construction and arrangement shown, as 65 many changes might be made therein with-

out departing from the spirit of my invention.

Having described my invention, what I claim as new and desire to secure by Letters Patent, is:

1. In combination, an endless concentrating belt of flexible material, means for folding said belt to form one or more channels, extending longitudinally of the belt, and means for gradually narrowing said channels along the concentrating zone. 70

2. In combination, an endless concentrating belt of flexible material, means for folding said belt to form one or more channels extending longitudinally of the belt, 80 means for gradually narrowing said channels along the concentrating zone, and means for expanding said channels after passing the concentrating zone.

3. In an automatically variable riffled endless belt concentrator, the combination of an endless belt, a supporting frame arranged to be adjustably tilted, means for imparting a reciprocative movement to said frame, of a plurality of rollers arranged on the frame 90 of said machine adapted to support the concentrating surface of said belt, and means connected with said rollers and including a series of collars and recessed portions and of flanges arranged and adapted to form 95 sunken riffles on said belts, and to automatically decrease the cross sectional area of said sunken riffles on the ore concentrating surface of said belt from its ore pulp feeding and receiving end to its concentrated 100 mineral discharging end.

4. A concentrator comprising an endless belt, means for folding the belt into riffles across its concentrating surface, and means for gradually decreasing the width of the 105 riffles from the feed end of said belt to its concentrates discharging end.

5. In a belt concentrator, the combination with a supporting frame, of an endless belt mounted thereon, means for automatically 110 folding said belt into a series of recess riffles, and means for gradually and progressively decreasing the cross sectional area of said recess riffles from the feed end of said belt to its mineral discharging end. 115

6. A belt concentrator provided with operatively arranged tilting and reciprocating mechanisms, means for automatically folding said belt into recessed or sunken riffles extending entirely across the mineral concentrating zone of said belt, and means for decreasing the cross section area of said recessed or sunken riffles continuously, and gradually along the concentrating surface of said belt from its ore pulp receiving end 120 to its concentrated mineral discharging end. 125

7. In a concentrator as specified, the combination with a suspended, reciprocable frame, of rollers mounted therein, and an endless belt upon said rollers, the rollers 130

3
being provided with stepped annular grooves whereby the belt is folded to form a series of sunken riffles which decrease in cross sectional area from the feed end to the discharge end of the belt.

8. In a concentrator as specified, the combination with a suspended, reciprocable frame, of rollers mounted therein, an endless belt upon said rollers, the rollers being 10 adapted to fold the belt into a series of sunken riffles, which decrease in width from the feed end of the machine, and means for widening the riffles on the return lap of the belt.

15. 9. In a concentrator as specified, the combination with a suspended, reciprocable frame, of annularly-grooved rollers at opposite ends of the frame, an endless belt on said rollers, endless flexible strips on said 20 belt which enter the grooves of said rollers, and a plurality of annularly grooved rollers disposed between said end rollers, said latter rollers and one of said end rollers having flanges between which and the strips the belt 25 is automatically folded into sunken riffles, which decrease in width in the direction of the travel of the belt, and means for widening the riffles on the return lap of the belt.

10. In a concentrator as specified, the combination with a suspended, reciprocable frame, of an annularly grooved roller at the feed end thereof, an annularly grooved roller at the discharge end thereof, and annularly-grooved rollers of smaller diameter, 35 disposed between said end rollers, the latter rollers and the discharge-end roller having flanges which increase successively in thickness from the feed end of the frame, an endless belt on said rollers, endless flexible strips 40 on said belt which enter the grooves of said rollers, said flanges being adapted to automatically fold the belt between them and the strips to form sunken riffles which decrease in width from the feed end of the 45 frame, and an annularly grooved roller beneath the discharge end roller, which is adapted to widen the riffles, on the return lap of the belt.

11. In a concentrator as specified, the combination with a suspended, reciprocable frame, rollers mounted therein, an endless belt on said rollers, means for automatically folding the belt to form sunken riffles which decrease in width from the feed end of the 55 frame, and means for widening the riffles on the return lap of the belt.

12. In a concentrator as specified, a suspended reciprocable frame, an annularly

grooved roller at the feed end of said frame, a succession of rollers of smaller diameter 60 having annular grooves alternating with stepped flanges, the step portions of which decrease in width successively from the feed end of the frame, with a corresponding increase in thickness of the flanges, a roller 65 at the discharge end of the frame of the same diameter as the feed-end roller, having alternating annular grooves and stepped flanges, an endless belt on said rollers, flexible 70 endless strips secured midway of their widths to said belt, and adapted to enter the grooves of said rollers, said strips being given a quarter turn to fold the belt between them, before they are placed in the grooves of the rollers, the flanges of said rollers and 75 said strips being adapted to form the said folded portions into riffles which decrease in width from the feed end of the frame, the bottoms of said riffles resting upon the step portions of the flanges, and a roller beneath 80 the discharge end roller adapted to widen out the riffles on the return lap of the belt.

13. In an endless belt concentrator, means for forming sunken riffles in the upper lap of the belt, which decrease in width toward 85 the discharge end of the belt, comprising annularly grooved supporting rollers, and endless resilient spaced strips on said belt, which enter said grooves, said belt being folded between said strips. 90

14. In an endless belt concentrator, means for automatically forming sunken riffles in the upper lap of the belt, which decrease in width toward its discharge end, and means for widening out the riffles on the return or 95 under lap of the belt.

15. In a belt concentrator as specified, the combination with a suspended reciprocable frame, of rollers mounted on said frame having alternating grooves and flanges, an 100 endless belt on said rollers, endless flexible strips on said belt which lie in the grooves of said rollers, portions of said belt being folded between said strips and the flanges of said rollers as the belt travels forward, 105 thereby forming riffles which decrease in width from the feed end of the belt, and beveled flanges on the feed side ends of said rollers for forming an upturned lip on the upper lap of said belt. 110

In testimony whereof I affix my signature in presence of two witnesses.

HENRY EGGERS.
